ILLUMINABLE SIGN

Hieme C. Hammer, 6N-130 Rte. 53, near Itasca, Ill.

Filed Nov. 8, 1961, Ser. No. 67,424

Term of patent 14 years

(Cl. D1—12)

FIGURE 1 is a perspective view of an illuminable sign showing my new design;

FIGURE 2 is a front elevation thereon;

FIGURE 3 is a reduced side elevation thereof;

FIGURE 4 is a reduced fragmentary side elevation thereof with parts shown in section;

FIGURE 5 is a reduced top plan view thereof; and

FIGURE 6 is a reduced fragmentary top plan view, thereof with parts shown in section.

It is to be understood that the fragmentarily shown protuberances on the inside of the spherical portion of the sign are continuous throughout said spherical portion.

I claim:

The ornamental design for an illuminable sign, substantially as shown and described.
